US00D953088S

(12) **United States Design Patent** (10) Patent No.: **US D953,088 S**
Seo et al. (45) Date of Patent: **** May 31, 2022**

(54) **ELECTRIC KETTLE**

(71) Applicant: **LG ELECTRONICS INC.**, Seoul (KR)

(72) Inventors: **Woonkyu Seo**, Seoul (KR); **Miyoung Kim**, Seoul (KR); **Hyun Choi**, Seoul (KR); **Hyeonjeong An**, Seoul (KR)

(73) Assignee: **LG ELECTRONICS INC.**, Seoul (KR)

(**) Term: **15 Years**

(21) Appl. No.: **29/726,106**

(22) Filed: **Feb. 28, 2020**

(30) **Foreign Application Priority Data**

Feb. 21, 2020 (KR) 30-2020-0007887

(57) **CLAIM**

The ornamental design for an electric kettle, as shown and described.

DESCRIPTION

FIG. 1 is a front, right side, perspective view of an electric kettle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side perspective view showing the claimed design removed from the base for clarity of understanding the disclosure.

The broken lines indicate portions of the article that form no part of the claimed design.

1 Claim, 8 Drawing Sheets
